[57] CLAIM

The ornamental design for a baby bottle holder, as shown and described.

DESCRIPTION

FIG. 1 is a top plan view of a baby bottle holder showing my new design;

FIG. 2 is a side elevation thereof;

FIG. 3 is a front elevation thereof;

FIG. 4 is a rear elevation thereof; and

FIG. 5 is a bottom plan view thereof.

The broken lines representing the baby bottle in FIG. 2 are shown for illustrative purposes only.

FIG. 1

FIG. 4
